Zabel & Mueller
Atg's.

UNITED STATES PATENT OFFICE.

SAMUEL BUCHSBAUM, OF CHICAGO, ILLINOIS.

CLASP.

Application filed October 20, 1919. Serial No. 331,840.

To all whom it may concern:

Be it known that I, SAMUEL BUCHSBAUM, a citizen of the United States, residing at Chicago, in the county of Cook and State 5 of Illinois, have invented a certain new and useful Improvement in Clasps, of which the following is a full, clear, concise, and exact description, reference being had to the accompanying drawings, forming a part of this specification.

My invention relates to clasps and more particularly to the clasp which is adapted to be secured to the end of a watch or other chain for attaching a watch, locket or any 15 other desired object to the end of the chain.

It is an object of the invention to provide a device of the character set forth which is simple, strong, durable, easy to manufacture and secure. In order to be 20 cheap there must be as few parts as possible and it is, therefore, a further object of the invention to provide a simple clasp which has the minimum number of parts. The clasp includes but two members, one of 25 which is movable on the other in order to provide the necessary opening for inserting the clasp into the eyelet of the object to be attached to the chain.

At the present time it is practically impossible to procure on the market and in 30 sufficient quantities the swivelled hooks which have as a general rule been used at the end of watch chains or similar chains. For this reason it is a further object of the 35 invention to provide a clasp which will serve all the purposes of the usual swivelled hook and will serve the required purpose equally as well.

In the drawings accompanying this specification I have disclosed one form of my invention, which form is the best known to me at the present time. However, it is to be understood that by this specification and the accompanying drawings I do not intend 45 to limit myself to the specific construction disclosed as modifications of the specific structure may be required in the manufacture thereof or may occur to those skilled in this art. The real nature and scope of 50 the invention disclosed is to be determined from the claims appended to this specifi-

cation. In the drawings where I have shown the preferred form of my device the same reference characters have been used to designate the same parts in the several 55 views. In the drawings—

Fig. 1 shows a side view of my clasp connecting a chain to a watch;

Fig. 2 is a side view partly in section of the clasp on an enlarged scale and showing the slideable element moved to open position.

Fig. 3 shows a slideable element removed in order to attach the chain to the clasp;

Fig. 4 is a front view of the clasp attached to a watch ring with the slideable element in closed position.

Fig. 5 shows a modified use of my clasp.

My improved clasp comprises but two parts, one of which is tubular and slides 70 upon the other in order to provide the opening necessary when the clasp is inserted through the eyelet of the object to which the chain is to be attached. The main element of my device is formed somewhat in 75 the shape of the letter B and comprises a straight portion 10, and a curved portion 11 to which the usual ring 12 at the end of the watch chain is attached. Beyond this curved portion which constitutes in fact an 80 eyelet for the reception of the ring 12 there is an inwardly bent portion 13 which extends nearly to the straight portion 10 of the clasp. Beyond the portion 13 there is a second curved portion 14 which in fact 85 constitutes a hook which is adapted to be inserted through the eyelet of the article in question. Beyond the curved portion 14 there is a second straight portion 15. The member just described is usually made of a 90 solid wire bent into the shape shown, but it will be very apparent that it may be made of hollow metal, if so desired. Furthermore, it is to be understood that while I have shown a clasp of a size adapted to be 95 worn at the end of a watch or other similar chain I do not intend to limit my invention to this specific use. If the clasp is made larger and stronger it may be used in place of the hooks now used on chains of all sorts. 100

The second element of my clasp consists of a tubular member 16 whose inside diameter

ter is substantially equal to the outside diameter of the element first described. When the principal element of my clasp is formed the free ends of the straight portions 10 and 15 are spaced apart as shown in the drawings. This provides the opening necessary to permit the curved hook portion 14 to be inserted through the eyelet of the object at hand. The element 16 is longer than the space between the free ends of the straight portions 10 and 15 so that it will bridge the open space between the ends in order to prevent the attached object from escaping between the ends.

15 The space 17 between the straight portion 10 and the curved portion 13 is less than the thickness of the walls of the tubular element 16. With this construction it will be apparent that when the element 16 is moved 20 to a position to bridge the free ends of the straight sections 10 and 15 that the straight portion 10 will spring toward the curved portion 13 and will effectively prevent the accidental return of the element 16. It is 25 to be understood, of course, that the metal forming the principal element of the clasp is elastic or resilient so that the straight portion 10 will move or spring toward the curved portion 13 as soon as it is free to do 30 so. The element 16 is prevented from moving further down on the straight portion 15 by reason of the shape or curvature just beyond the portion 15.

The operation of my clasp is as follows: 35 When it is desired to attach the clasp to the ring of a watch the element 16 is moved along the straight portion 10 as shown in Fig. 2 of the drawings. The watch ring can then be inserted through the open space 40 between the free ends of portions 10 and 15 whereupon the member 16 will be moved back to its normal or locking position as shown in Fig. 1.

In many cases the ring 12 will be a split 45 ring so that when it is desired to attach the clasp to a chain the ring 12 will be sprung open in the usual manner and thereafter closed around the portion 11 of the clasp. If the ring 12 is not a split ring then it will 50 be connected to the clasp as follows:

The element 16 will be moved along the portion 10 until its outer end is free of the end of the portion 15. The operator may then spring the element 16 and the straight 55 portion to one side until the element 16 is free to pass beyond the end of the portion 15. The element 16 can then be entirely removed from the straight portion 10 and the ring 12 can be slipped over the portion 10, 60 through the space 17 and onto the curved portion 11 of the clasp. After this the element 16 will be positioned on the straight portion 10 and moved back to its normal or locking position.

65 From what has been described it will be

very apparent that I have devised a neat, simple, strong, and effective clasp which is especially adapted for use on watch or similar chains. There are no complicated parts to get out of order and no springs to weaken. 70 The metal of which the clasp is made is resilient enough to operate in the manner set forth.

In Fig. 5 I have shown my clasp used for attaching a fish hook to the line. The line 75 18 is provided with a loop 19 at its end through which the portion 11 of my clasp is adapted to extend. The fish hook 20 is provided as is usual with the gut extension 21 which has at its free end the loop 22 80 through which the portion 14 of my clasp may extend. The method of securing the hook to the line is the same as that outlined above. It will be very apparent that there are no sharp corners projecting which 85 would catch in the reeds and the clasp is therefore very well adapted for the purpose set forth.

Having thus described my invention what I claim as new and desire to secure by 90 United States Letters Patent is:

1. A clasp of the character described comprising a straight portion, a curved portion forming an eyelet, a second curved portion spaced from said straight portion, and a 95 hook-shaped portion in combination with a tubular element slidable on said straight portion, the space between said straight portion and the second named curved portion being slightly less than the thickness of the 100 walls of said tubular element.

2. A clasp of the character described comprising a main element having a hook shaped portion, and a straight portion aligned with the end of said hook shaped 105 portion, a tubular member slidable on said straight portion and adapted to engage said hook shaped portion to close the opening in said hook and a stop on said main member opposite said straight portion and extending toward said straight portion to retain 110 said slidable member in hook closing position.

3. A clasp of the character described comprising a main element having a hook 115 shaped portion, and a straight portion, a tubular member slidable on said straight portion and adapted to engage said hook shaped portion to close the opening in said hook and a stop on said main member opposite said straight portion to retain said 120 slidable member in hook closing position, said stop and said straight portion cooperating to retain said slidable member in inoperative position when said member is moved 125 therebetween.

4. A clasp of the character described comprising a main element of resilient material having a hook shaped portion, and a straight portion, a tubular member slidable 130

on said straight portion and adapted to engage said hook shaped portion to close the opening in said hook and a stop on said main member opposite said straight portion 5 to retain said slidable member in hook closing position, said stop and said straight portion cooperating to retain said slidable

member in inoperative position when said member is moved therebetween.

In witness whereof, I hereunto subscribe 10 my name this 17th day of October, A. D., 1919.

SAMUEL BUCHSBAUM.
